FORMATION OF THE ROLL OF TOBACCO IN
CIGARETTE-MAKING MACHINESMichel Rault, Sceaux, France, assignor to Societe
Anonyme Usines Decoufle, Paris, France

Application February 14, 1949, Serial No. 76,294

4 Claims. (Cl. 131—84)

1

The present invention is concerned with apparatus used for tobacco distribution in continuous roll cigarette making machines, which machines usually comprise special carding drums adapted to supply tobacco from the tobacco in the bulk fed from a suitable container or supply means.

The tobacco for cigarettes is supplied from the distributor in the form of a shower of loose staples which is laid on a traveling belt as uniformly as possible and the belt conveyor is adapted to bring it to a tobacco roll forming means and thence to a cigarette forming means.

In spite of the arrangements devised heretofore to improve the uniform pickup or "taking" of the tobacco by the carding drums or to subsequently compensate for the lack of uniformity of such a "taking," the tobacco sliver present on the belt conveyor is far from being uniform. The tobacco stream exhibits pits and knolls, or, nodes and antinodes, which upon being taken by the tobacco roll former mechanism and the cigarette forming mechanism leads to the production of cigarettes which are not uniform and each quite different in weight, compactness and amount, which results in loss of quality in the cigarette and in wastefulness in manufacture.

This lack of uniformity is thus ascribable to the unsatisfactory loading of the carding device and also to a greater or lesser density of the tobacco staple shower falling upon the conveyor. There are further disadvantages resulting in the considerable variations in the weights of the cigarettes which are ascribable to an unsteady output of the distributor, the origin of which is to be found in the variations in physical condition of the tobacco and in the heterogeneous character of the mass.

The final result is that in conventional designs of cigarette making machines the tobacco sliver conveyed on the belt and fed as such to the processing members is converted into a compacted roll and then into a cigarette with the above indicated defects which must be accepted despite these disadvantages.

The present invention overcomes these disadvantages of the prior art devices.

An object of the invention is directed to a method of forming a tobacco filler of uniform size and consistence for the manufacture of cigarettes in a continuous-filler cigarette machine which method feeds tobacco from a distributor in a continuous stream, on a flexible endless support, the tobacco being fed having an amount in cross section which is in excess of that amount in cross section of a finished cigarette, and selectively narrows the stream in a transverse direction by the successive converging of the stream from a lateral pressing against the endless support, the particles of tobacco being held down by gravity and other particles only throughout the whole length of the stream up to the point where the excess portion is to be re-

2

moved from the top of the stream, and divides and removes the excess portion from the top of the stream above a predetermined level.

A further object of the invention is directed to the return of the excess tobacco in the series of operations indicated in the foregoing paragraph, the excess tobacco being returned to said distributor.

Other and further objects of the present invention will appear from the more detailed description set forth below, it being understood that such more detailed description is given by way of illustration and explanation only and not by way of limitation.

The principle of the invention resides in that once the distributor is set to deliver an excess of tobacco over what is necessary to obtain cigarettes of the desired mean weight, the knolls are removed from the sliver at a suitably chosen place, the tobacco stream being held down solely by gravity and only a uniform sliver that will form correct cigarettes is allowed to proceed towards the cigarette machine. The surplus tobacco thus removed is brought back into the distributor in order that it shall not get lost.

An embodiment will now be described more specifically which is based upon the reasonably exact assumption that the density of the tobacco as deposited on the belt conveyor remains constant, i.e. that the weight of tobacco which is thus deposited in loose although more or less interlocked staples is constant for a given volume.

In this assumption, the invention aims at securing a tobacco sliver of constant volume. On the whole, the following procedure may be adopted:

1. Setting the distributor to deliver a tobacco sliver that contains more tobacco than is necessary to obtain cigarettes of the desired mean weight and consequently the sectional area of which will be larger than the one corresponding to the desired mean weight; determining such a surplus so that even in those regions of the tobacco sliver in which pits are present due to lack of uniformity in the supply the section of the sliver shall be at least equal to the section corresponding to the desired mean weight.

2. At a definite point in the travel of the tobacco sliver, removing the tobacco present in excess over the section just mentioned.

3. Allowing only the tobacco sliver portion which just fills said section to proceed and form the cigarette, and returning the remainder to the bulk of tobacco in the distributor.

For the formation of the cigarette, a flow of tobacco of constant density is thus obtained which is free from knolls as well as from pits provided a sufficient excess of tobacco is delivered by the distributor. The uneven surface portions of the sliver are removed with the removal of the excess tobacco.

It has been revealed by practice that in this

manner the lack of uniformity in the weights of the cigarettes is lessened considerably, and so is the diversity in compactness and filling.

In fact, residual differences may subsist, which are ascribable notably to the fact that the weight of tobacco per unit of length of the sliver thus "topped" varies, in other words the density of the tobacco is not constant all along the roll. Such residual differences are not considerable.

Naturally, the "topping" mechanism should be arranged in the machine as far downstream as possible, that is, at the latest moment before the cigarette forming operations.

An embodiment of the mechanisms whereby the method thus defined is illustrated by way of example in the drawing appended hereto.

Figure 1 is a diagrammatic vertical cross-section of the apparatus in which the method of the invention is carried out.

Figure 2 is a vertical section of detail of the apparatus of Figure 1 taken on the section line II-II of the tobacco sliver.

Figures 3, 4 and 5 are sectional views of the detail of Figure 2 taken respectively on lines III-III, IV-IV and V-V in Figure 2.

Figures 6 and 7 are longitudinal sections showing inequalities in the tobacco sliver on the conveyor.

Figures 8 and 9 are a vertical section and a plan view, respectively, of a knife means to divide and separate the top portion of the sliver.

Figure 10 is a partial vertical sectional view, and Figure 11 a plan view, respectively, of still another device to separate the excess of tobacco from the tobacco stream.

Figures 12 and 13 are a vertical section and plan view, respectively, of a topping device or shears utilized for dividing and separating the excess of tobacco from the tobacco stream.

Figure 14 is a plan view of a mechanism for the removal of the excess tobacco.

Figure 15 is a sectional view of a modification of the adjusting mechanism.

Figure 16 is a plan view of a further embodiment of the invention.

Figures 17, 18 and 19 are cross sectional views taken respectively on lines XVIII-XVIII and XIX-XIX in Fig. 2.

The distributor illustrated in Figs. 1 and 2 comprises as its main elements:

A hopper 1 for the bulk tobacco 1a,

A tobacco feed card 2,

A tobacco leveling card 3,

A return pipe 29 for returning the excess tobacco to the distributor, and

A belt conveyor 6 on which the tobacco falls when loosened and a delivery hopper 5 open at its lower end through which the tobacco is dropped as a shower onto the said belt conveyor 6 shown in horizontal sectional view.

The endless belt conveyor 6 is visible in its entire extent in Fig. 2. The tobacco sliver 7 which forms on the belt due to the falling of the tobacco staples from the delivery hopper 5 is limited by the cross walls 8 and 9. The formation of the tobacco sliver begins directly below the wall 8 and is completed directly below the wall 9, whence it is conveyed on the belt 6 towards the cigarette forming members.

By way of example, in the machine, the tobacco sliver after being divided in accordance with the invention is passed below a compression disc 10 on its way from the orifice of the hopper 5 and the tobacco sliver is caused progressively, by moving in a fixed channel, to assume a shape that

is U-shaped in cross-section, and it is in the bottom of the U-shaped channel (see Figs. 4 and 5) that the sides of the U are progressively formed. Due to the pressure exerted by the disc 10 it becomes compacted on the paper 33 to a section approximating that of the cigarette.

The progress of such a formation of the roll of tobacco once the latter has left the distributor and moved past the wall 9 is shown rather diagrammatically in Figs. 3, 4 and 5. Indicated at 11 is the sectional shape of the tobacco roll as laid on the belt 6 (Fig. 3). At 12 (Fig. 4) the said section has narrowed and the tobacco occupies a thicker section than in Fig. 3. As shown in Fig. 5 the section 13 becomes progressively smaller and the tobacco is compressed.

On account of the pits and knolls presented by the tobacco sliver due to the aforementioned lack of uniformity of the staple, the sliver as it enters the section III (Fig. 2) has a sectional aspect which is diagrammatically indicated in Fig. 6, which is well-known to those skilled in the art. In section IV the said uneven surface portions are amplified and result in differences in thickness which are indicated roughly in Fig. 7. Indeed, they will no longer be visible once the disc 10 has accomplished its compacting action, yet, they will none the less be still present thereafter in the constant-section roll in the form of hard overpressed places alternating with soft places at which the cigarette will deform and be mashed easily if pressed between one's fingers.

In accordance with the invention, the tobacco in the section IV is "topped" or divided to a constant height h (Fig. 7) which is less than the thickness of the tobacco sliver at those places where the pits are the deepest and the tobacco which lies above the level h is thrown aside to be returned to the hopper 1 in piping 29 schematically shown in Figure 1. A tobacco sliver of uniform thickness is thereby obtained.

More than the usual amount necessary of tobacco is delivered by the distributor since only that portion which remains below the level h constitutes the tobacco portion of the cigarettes.

Various arrangements may be contemplated for the purpose of shearing off the excess tobacco above the level h . One amongst them consists in the provision in the section IV (in which the height h is determined by the height of the fixed sides that contain the tobacco sliver) of a pair of cutter discs 14 and 15 (Fig. 8) that slightly overlap one another in contact with each other and that are rotated in opposite directions at a speed sufficient to shear off the excess tobacco without dragging the flow that moves on below the level h . Figure 8 is a sectional view and Fig. 9 a plan view of such an arrangement. For this same purpose shears 15 is shown in Figure 2.

A blowing nozzle 24 or any other suitable device is provided whereby the excess tobacco which accumulates on top of the cutter discs 14, 15, after the shearing process, is rejected aside to be taken again by suitable means (not shown) and returned to the bulk of fresh tobacco in the distributor.

In lieu of the blowing nozzle it is possible e. g. to use a pair of lateral belts 25 (see Fig. 14) driving dividing rollers 14a and 15a, said belts running in continuous motion and adapted to convey the top layer of the tobacco sliver towards a guide 26 by which it is discharged outwards; the said belts and guide positively convey the excess tobacco to tobacco conveyors by which it will be returned to the distributor.

The cutter discs 14 and 15 are driven through mechanical transmission means (not shown) from the main driving shaft of the machine.

Means are provided to control the average weight of the cigarette obtained in the above described process. These means are adapted to obtain said average weight by adjusting the size of the tobacco section 13 in that region of support 31 wherein the tobacco flows beneath the cutters 14 and 15. For example, the block 17 that supports the bottom of the tobacco roll in that region (see Fig. 8), may be made adjustable vertically by means of set screw 16.

For the same purpose it is also possible to narrow the bottom portion of the roll by means of a pair of side plates 27, the spacing of which can be adjusted with the aid of means indicated at 28 in Fig. 15.

Various modifications of the topping means may be contemplated within the scope of the invention. For instance the sliver may be compelled to progressively assume an almost cylindrical shape (delimiting a cross-sectional circular area equal to the standard sectional area of the loose tobacco roll), the surplus that stands above the topping plane thus being in some manner severed from the residual roll in the form of a tuft that projects above the strike-off plane. In that case the compacting of the tobacco will make it easier to strike-off the excess with the aid either of cutter discs or shears as shown in Figures 2, 8, 9 and as described hereinbefore or of a spiked cylinder 22 (see Figs. 11, 12) arranged diagonally above the strike-off plane and rotated at high speed. The excess tobacco is torn off by the spikes and whirled aside to be returned to the distributor.

A strike-off device 23 for the excess tobacco may be provided, instead of the spiked cylinder 22 of Figs. 11 and 12, the strike-off device provided with a toothed edge which is placed transversely across the advancing tobacco stream at the proper level for the removal of the excess of tobacco, so as to operate in the fashion of a mowing machine and is illustrated in Figs. 12 and 13.

In the embodiment shown in Fig. 2 the channel and belt conveyor in the section which is located below the distributor (from wall 8 to wall 9 in Fig. 2) are arranged as shown in Fig. 3. In the section next to said wall 9 the channel and belt assume a U-shape as illustrated in Figs. 4 and 8. To overcome the defect of this arrangement wherein the channel and belt are converted too abruptly from the cross-section in Fig. 3 to the one shown in Fig. 4, the modification is made as shown in Figs. 17 and 19, to progressively transform the section of the said channel within that section which is comprised between the walls 8 and 9 so as to delimit the distributor longitudinally as illustrated in Figs. 17 to 19. At the entrance of the distributor the belt 6 is flat (Fig. 17), after which at the exit it assumes an inverted hog back-like section (Fig. 18).

Having thus disclosed the invention what is claimed is:

1. The method of forming a tobacco filler of uniform size and consistence for the manufacture of cigarettes in a continuous-filler cigarette machine comprising the steps of feeding tobacco from a distributor in a continuous stream, the tobacco being fed having an amount in cross section which is in excess of that amount in cross section of a finished cigarette, selectively narrowing the stream in a transverse direction, said tobacco stream having its particles of tobacco

held down by gravity and other particles of tobacco only throughout the whole length of the stream up to the point where the excess portion is to be removed from the top of the stream and dividing and removing the excess portion from the top of the stream above a predetermined level.

2. The method of forming a tobacco filler of uniform size and consistence for the manufacture of cigarettes in a continuous-filler cigarette machine comprising the steps of feeding tobacco from a distributor in a continuous stream, the tobacco being fed having an amount in cross section which is in excess of that amount in cross section of a finished cigarette, selectively narrowing the stream in a transverse direction, said tobacco stream having its particles of tobacco held down by gravity and other particles of tobacco only throughout the whole length of the stream up to the point where the excess portion is to be removed from the top of the stream and dividing and removing the excess portion from the top of the stream above a predetermined level, said excess tobacco being removed at a point closely adjacent the place where the selectively narrowing operation has been completed.

3. The method of forming a tobacco filler of uniform size and consistence for the manufacture of cigarettes in a continuous-filler cigarette machine comprising the steps of feeding tobacco from a distributor in a continuous stream on a flexible endless support, the tobacco being fed having an amount in cross section which is in excess of that amount in cross section of a finished cigarette, successively converging the stream by laterally pressing against the endless support, said tobacco stream having its particles of tobacco held down by gravity and other particles of tobacco only throughout the whole length of the stream up to the point where the excess portion is to be removed from the top of the stream and dividing and removing the excess portion from the top of the stream above a predetermined level.

4. The method of forming a tobacco filler of uniform size and consistence for the manufacture of cigarettes in a continuous-filler cigarette machine comprising the steps of feeding tobacco from a distributor in a continuous stream on a flexible endless support, the tobacco being fed having an amount in cross section of a finished cigarette, successively converging the stream to narrow it in a transverse direction by laterally pressing against the endless support, said tobacco stream having its particles of tobacco held down by gravity and other particles of tobacco only throughout the whole length of the stream up to the point where the excess portion is to be removed from the top of the stream, dividing and removing the excess portion from the top of the stream above a predetermined level in a lateral direction from the path of the stream and returning the excess tobacco to said distributor.

MICHEL RUAULT.
